PROTECTIVE ATTACHMENT FOR WOMEN'S UNDERGARMENT

Elizabeth M. Neumayer, Astoria, N. Y.

Application March 27, 1950, Serial No. 152,161

4 Claims. (Cl. 2—46)

1

This invention relates to undergarments for women and is particularly directed to a protective insert which may be attached to undergarments such as slips, underskirts and petticoats.

The attachment is designed primarily for undergarments worn by women during the menstrual period, or other period, to prevent the transmission of moisture formed by the body to the outer garments worn by the woman.

While undergarments of this general character have been available, they have been made in such a manner that it has been difficult or impossible to launder the garment, so that it was necessary to destroy it after it was soiled. Other garments for this purpose have been costly to produce and difficult to put on, or extremely uncomfortable to the body of the wearer.

The principal object of my invention is to produce an undergarment, which is fitted with a detachable, waterproof insert, and can be worn in the same manner as the conventional undergarment.

A further object is to provide an undergarment which can be laundered and ironed, in the same manner as the conventional undergarment.

Another object is to provide an undergarment which can be worn, with or without the protective insert.

A primary object is to provide a simple, relatively inexpensive undergarment, in which the body is protected from contact with rubber sheeting, or similar waterproof materials, and which, in outward appearance, resembles the conventional undergarment.

Another object is to provide an attachment which can be applied to undergarments of various forms and types, made in a wide range and variety of materials.

The accompanying drawings, illustrative of one embodiment of my invention, and several modifications thereof, together with the description of their construction and the method of utilization thereof, will serve to clarify further objects and advantages of my invention.

In the drawings:

Fig. 1 represents a modified perspective view of one type of underskirt, fitted with a protective attachment.

Fig. 2 is a front elevation of the rear portion of the underskirt, shown in Fig. 1.

Fig. 3 is a front elevation, similar to Fig. 2, of a modification of the underskirt, shown in Figs. 1 and 2.

Fig. 4 is a cross-section through the rear portion of the underskirt of Figs. 1 and 2, taken at 4—4, Fig. 2.

2

Fig. 5 is a cross-section through the rear portion of the underskirt of Fig. 3, taken at 5—5, Fig. 3.

Fig. 6 is a cross-section through the upper snap-fastener of Fig. 3, taken at 5—5, Fig. 3.

Fig. 7 is a cross-section, similar to Fig. 6, showing a modified type of fastener.

Fig. 8 is a front elevation of a modification of the rear panel of the underskirt of Figs. 2 and 3.

It will be understood that the following description of the construction and utilization of the "protective attachment for women's undergarment," is intended as explanatory of the invention and not restrictive thereof.

In the drawings, the same reference numerals designate the same parts throughout the various views, except where otherwise indicated.

One embodiment of the undergarment, shown in Figs. 1 and 2 is in the form of an underskirt, made of cotton, rayon, or other suitable material, although substantially the same construction can be applied to a slip, petticoat, or other similar undergarment.

The underskirt 10 may be made of one or more sheets of material, cut in the form of a rear section or panel 11, and a front section or panel 12, formed integral therewith, or sewed thereto, the ends of the two panels being connected by a seam at one side. A belt 14 may be formed at the upper end of the panels, the ends of the belt being detachably connected by a plurality of snap fasteners 15, or other suitable form of fastener.

A reinforcing lining 16 may be attached to the rear section 11, of the underskirt, seams 17 and 18 being sewed along the sides and bottom of the lining and rear section, respectively, with the upper and left unstitched. A plurality of tabs 20 may be sewed to the rear section of the garment, below the belt, the ball element 21, or the socket element 22, of a snap fastener, being attached to the free end of each of the tabs, as indicated in Figs. 2 and 4.

A plurality of similar tabs 23 may be attached to the upper end of the lining, with the mating elements 21 or 22 of the snap fasteners, attached to the tabs, or attached through the tabs and the lining material, the ball and socket sections of the snap fasteners removably attaching the upper end of the lining to the rear section of the garment.

An insert 24, made of a thin, transparent plastic material such as "Pliofilm," "Saran," or any other suitable water-proof, thin plastic sheet, may be inserted between the rear section of the garment and the lining, as indicated in Figs. 2 and 4; a reinforcement or hem 25, being

formed around the edges of the insert, the edges of the hems being attached to the insert proper by stitching 26, heat sealing, or other suitable means.

A plurality of similar fabric tabs 29 may be attached to the bottom of the lining, or stitched to the bottom seam joining the lining to the rear section of the garment, one element 21 or 22, of the ball snap, or other suitable type of fastener, being attached to the tab, with the mating element of the fastener attached to the hem of the insert, the fasteners providing a detachable means for connecting the insert to the garment.

A plurality of openings 30 may be formed along the hem, at the upper end of the insert, in substantial alignment with the snap fasteners 15, a ring-shaped washer or reinforcement 31, made of a plastic material, fabric, thin sheet metal, or other suitable material, being attached to one or both sides of the plastic material, around the opening, by gluing, heat sealing or other suitable means, to reinforce the material of the insert around the opening.

The ball end 21, of each of the upper snap fasteners projects through the corresponding opening in the insert, thus clamping the upper end of the insert between the fastener elements 21 and 22, connecting the upper end of the lining to the rear section of the garment, thereby supporting the upper end of the insert between the lining and the garment section.

The sides 32 of the insert may be left unattached, as indicated in Fig. 2, the insert being supported between the lining and the rear section of the garment, or a plurality of snap fasteners, may be used to attach the sides of the insert to the lining 16 in the same manner as those shown at the bottom of the insert.

In this manner, the insert 24 may be removed, or replaced when it becomes soiled, without disturbing either the lining 16, or the body of the garment, thus enabling the user to wear the garment, either with or without the insert.

The balance of the garment, with the insert removed, being made entirely of a fabric, may be laundered and ironed, in the conventional manner, the method of laundering depending upon the material used.

In a modification of the construction, shown in Figs. 3 and 5, the tabs 20 and 23 attached to the upper section of the lining, and the lower tabs 29, shown in Fig. 2, may be eliminated.

Where a heavy fabric material is used, the ball elements 21 of the fasteners may be attached directly to the upper end of the lining, the sockets 22, of the fasteners, being attached to the rear section 11 of the garment, or the ball and socket portions of the fasteners may be reversed.

The insert 24 is substantially the same as that shown in Figs. 2 and 4 and hereinbefore described, the openings 30, formed in the hem of the insert, fitting over the ball of the fastener, with the insert clamped between the rear section 11, of the garment, and the lining. Reinforcements 31, similar to those shown in Fig. 4, and hereinbefore described, may be attached to the insert in substantially the same manner.

The bottom of the lining 16 may be attached to the rear section 11, of the garment, in substantially the same manner, as that shown in Figs. 2 and 4 and hereinbefore described. The ball or socket elements 21 or 22, of the fasteners, may be attached directly to the fabric of the lining, with the mating elements, attached to the

insert, the insert being supported by the fasteners, in the manner hereinbefore described.

In another modification of the construction, shown in Fig. 7, the ball section 21, of a special dual snap fastener, would be attached to the rear section 11 of the garment, or to a tab, attached to the rear section, with the socket element 22, attached to the lining 16, or a tab attached to the lining, in substantially the same manner, as those shown in Figs. 2 and 3.

A plurality of dual intermediate fastener elements 33, each comprising a ball at one side, adapted to fit the socket of the other fastener element 22, and a socket, formed in the rear portion of the element, adapted to receive the ball, of the ball element 21, may be attached to the hem of the insert, in place of the openings shown in Fig. 4.

In this manner, the insert may be removed, and the lining attached to the rear garment section, by connecting the ball and socket elements of the fasteners, or the special combination elements 33, may be interposed between the ball and socket elements, as indicated in Fig. 7, to detachably support the insert.

In order to render the lining 16 completely detachable, the seam 18, at the bottom of the lining may, be eliminated, a pair of slide fastener tapes 36 and 37, being sewed to the bottom of the lining 16, and the bottom of the rear section 11 of the garment, as indicated in Fig. 8, a pair of separators 38, being attached to the tapes below the end elements of the fastener, to enable one section of the fastener, attached to the lining, to be removed without disturbing the body of the garment.

The upper portion of the lining may be attached to the rear section 11 of the garment, in the manner shown in Figs. 2 and 3 and hereinbefore described.

The upper and lower end of the insert may be interposed between the lining and the rear section of the garment and attached to the rear section and the lining by means of snap fasteners 15, in the manner shown in Figs. 2 and 3, and hereinbefore described.

The sides of the lining 16 may be left free, or attached to the sides of the rear section of the garment by means of a plurality of snap fasteners 15, to render the lining and insert completely detachable.

The garment may be made in the form of an underskirt, as indicated in Figs. 1, 2 and 3, or the upper portion may be added to form a complete slip, without disturbing the lining, or the insert in any manner.

The garment proper and the lining may be made of a fabric, such as cotton, rayon, or other suitable material.

The snap fasteners may be of the ball and socket type, or any other suitable type of fastener, which functions in a similar manner.

The insert may be made of one of a number of thin sheets of transparent, translucent, or other suitable type of plastic material, which is impervious to moisture, or a thin fabric, impregnated in such a manner as to render it water-proof may be substituted therefor.

It will be apparent to those skilled in the art that my present invention is not limited to the specific details described above and shown in the drawings, and that various further modifications are possible in carrying out the features of the invention without departing from the spirit and scope of the appended claims.

What I claim is:

1. In an undergarment formed of a front and rear section, a lining mounted inside the rear section, means attaching the side edges of said lining to the rear section, a plurality of snap fastener elements attached to the upper edge of the rear section of the undergarment, a plurality of mating snap fastener elements attached to the upper edge of the lining, in substantial alignment with the rear section upper edge fastener elements, said snap fasteners removably attaching the upper edge of the lining to the rear section, a water-repellent insert interposed between the lining and the undergarment rear section, the upper edge of said insert having a plurality of openings therein in substantial alignment with the adjacent rear section upper edge snap fastener elements, a flat ring-shaped reinforcement attached to the liner around each of said openings, the projecting end of the fastener elements attached to the rear section upper edge fitting through the liner openings and the reinforcements surrounding them to clamp the insert between the fastener elements connecting the upper edge of the lining to the garment rear section, a plurality of snap fastener elements attached to the bottom edge of the lining, a plurality of mating snap fastener elements attached to the bottom edge of the insert in substantial alignment with the lining bottom edge snap fastener elements, said snap fastener elements removably attaching the bottom edge of the insert to the lining.

2. In an undergarment formed of a front and rear section, a lining mounted inside the rear section, means attaching the side edges of the lining to the rear section, a plurality of tabs attached to the upper edge of said lining, a plurality of tabs attached to the upper edge of the rear section in substantial alignment with the tabs attached to the lining, a snap fastener element attached to each of said tabs attached to the rear section upper edge, a mating fastener element attached to each of the tabs attached to the lining, said snap fasteners removably attaching the upper edge of the lining to the rear section, a water-repellent insert interposed between said lining and the rear section, the upper edge of said insert being clamped between the snap fastener sections, connecting the upper edge of the lining to the rear section, a plurality of tabs attached to the bottom edge of the rear section of the garment, and a snap fastener element attached to each of said rear section bottom edge tabs, the mating fastener elements being attached to the bottom edge of the insert, said fasteners removably supporting the bottom edge of said insert.

3. In an undergarment formed of a front and rear section, a lining mounted inside the rear section, means attaching the side edges of the lining to the rear section, a plurality of snap fastener elements attached to the upper edge of

the rear section, of the garment, a plurality of mating snap fastener elements attached to the upper edge of the lining, in substantial alignment with the rear section upper edge snap fastener elements, said snap fasteners removably attaching the upper edge of the lining to the rear section, a water-repellent insert interposed between said lining and the rear section, the upper edge of said insert having a plurality of openings formed therein in substantial alignment with the lining fasteners, the projecting end of one set of said fastener elements fitting through said openings to clamp the insert between the fastener sections, connecting the upper edge of the lining to the rear section, and a plurality of snap fastener elements, attached to the bottom edge of the lining, the mating fastener elements being attached to the bottom edge of the insert, in substantial alignment with the lining bottom edge fastener elements, said fasteners removably supporting the bottom edge of said insert.

4. In an undergarment formed of a front and rear section, a lining mounted inside the rear section, means attaching the side edges of the lining to the rear section, a plurality of tabs attached to the upper edge of said lining, a plurality of tabs attached to the upper edge of the rear section in substantial alignment with the tabs attached to the lining, a snap fastener element attached to each of said tabs attached to the rear section, a mating snap fastener element attached to each of the tabs attached to the lining, said fasteners removably attaching the upper edge of the lining to the rear section, a water-repellent insert interposed between said lining and the rear section, the upper edge of said insert being clamped between the upper edge snap fastener sections, connecting the upper edge of the lining to the rear section, a plurality of tabs attached to the bottom edge of the rear section of the garment, a snap fastener element, attached to each of said tabs attached to the rear section bottom edge, the mating fastener elements being attached to the bottom edge of the insert, in substantial alignment with the fastener elements attached to the rear section bottom edge tabs, said fasteners removably supporting the bottom edge of said insert.

ELIZABETH M. NEUMAYER.
